UNITED STATES PATENT OFFICE

147,849

DESIGN FOR AN ASH TRAY OR SIMILAR
ARTICLE

David C. Henderson, Des Plaines, Ill., assignor to
Cruver Manufacturing Company, Chicago, Ill.,
a corporation of Illinois

Application July 5, 1946, Serial No. 131,327

Term of patent 7 years

(Cl. D85—2)

To all whom it may concern:

Be it known that I, David C. Henderson, a citizen of the United States, residing in the village of Des Plaines, county of Cook, and State of Illinois, have invented a new, original, and ornamental Design for an Ash Tray or Similar Article, of which the following is a specification, reference being had to the accompanying drawing, forming a part thereof.

Fig. 1 is a perspective view of an ash tray showing my new design.

Fig. 2 is a side elevational view thereof.

Fig. 3 is an end elevational view thereof.

Fig. 4 is a top plan view thereof.

I claim:

The ornamental design for an ash tray or similar article, substantially as shown.

DAVID C. HENDERSON.
